APPARATUS FOR SURFACE HARDENING
METAL ARTICLES

Hermann Holler, Frankfort-on-the-Main, Germany, assignor to I. G. Farbenindustrie Aktiengesellschaft, Frankfort-on-the-Main, Germany

Application December 17, 1935, Serial No. 54,923
In Germany December 29, 1934

2 Claims. (Cl. 266—5)

The present invention relates to an apparatus for surface hardening metal articles.

Surface hardening of metal articles by means of the blow pipe flame has been carried out by means of apparatus by which the burner is positively driven in a suitable manner over the article to be hardened. This method of hardening has also been carried out by apparatus which automatically applies the burner to the article at the beginning of its movement and removes it when this movement is finished.

For hardening numerous articles, however, it is necessary to move the burner over the article at variable speeds, the speed in each case being determined in accordance with the degree of hardness desired. Especially is this done when hardening toothed wheels. In this application the burner must, when placed over the tooth to be hardened, remain in this position until the relatively cold tooth is heated sufficiently. When this heating is finished the burner may be moved over the tooth flank but its velocity must be accelerated as it approaches the end of the tooth in order that overheating of this part of the toothed wheel is avoided.

When surface hardening bevel wheels, for example, where the thickness of the tooth is not constant along its width, the requirements with regard to the burner speed are more difficult to meet.

An object of the present invention is to provide a device which permits the velocity of the burner to be adjusted to suit a particular article.

My invention is practiced by moving the burner over the article to be hardened while automatically controlling its motion and driving it by operation of a driving member to which is imparted an always constant speed of rotation. The necessary adjustment of the velocity of the moving burner is accomplished by positively changing the direction of movement of the driving member, and by transmitting the effect of this change to the moving burner through a sliding arm between the driving member and the burner carriage.

The invention is illustrated by way of example in the accompanying drawings in which

Fig. 1 is an elevation,

Fig. 2 a plan, and

Fig. 3 illustrates diagrammatically a bevel wheel to be hardened, while

Fig. 3a illustrates the cam plate used when hardening the bevel gear of Fig. 3,

Figs. 4 and 5 illustrate details of the drive

mechanism of the arrangement shown in Figs. 1 to 3.

Referring to the drawings, a frame 1 carries a carriage 2 which can be adjusted to a desired position on the frame and which supports for movements thereon a burner carriage 3. In the latter carriage an arm 4 is slidably mounted on rollers 15 in a guideway 16 for reciprocating movement in a direction transversely of the movement of the burner carriage 3. The arm is held in the guideway 16 by guide-rails 17. The arm 4 is moved by a wheel 5 which is driven by a motor 13, as more distinctly shown in Fig. 4, and which is constrained by means of a solenoid 12 situated in a casing, to follow the path of a fixed cam plate 6, the shape of which is determined according to the particular requirements imposed by an article to be hardened. The wheel 5 is driven with a constant velocity. When, for example, a normal toothed wheel shown in Figs. 1 and 2 is to be hardened the burner is, at the commencement of the hardening process, positioned adjacent the left top edge of a wheel tooth. The wheel 5 at this moment is at the left rear corner 10 of the cam plate 6. Wheel 5 now runs forwardly, i. e. towards the toothed wheel on the plate as indicated by an arrow in Fig. 2. As the arm 4 which carries the wheel 5 is slidably arranged in the burner carriage 3, the burner, which is fixed to its carriage, is not moved during the forward movement of the wheel 5. As soon as the wheel 5 rounds the left front corner of the plate 6 it moves to the right as shown by the arrow in Fig. 2 at a constant velocity and thereby moves the burner to the right over the wheel tooth until the edge is reached. At the end of this movement the wheel 5 rounds the right front corner of the plate 6 and returns to its initial position by moving over the hypotenuse of the triangular cam plate 6 in the direction indicated by the inclined arrow in Fig. 2. For this purpose the driving wheel 5 is, when the heating has been finished, brought away from the action of the cam plate 6 in a manner more distinctly defined below and the burner carriage 3 is drawn back into its initial position with an elevated velocity by means of a weight 11.

When, instead of a normal toothed wheel a bevel wheel, as shown in Fig. 3, is to be hardened, a fixed cam plate of the shape shown at a_1 in Fig. 3a is used. In this case the speed of the burner as it moves along a tooth is not constant but varies according to the kind of toothed wheel as can be seen from the shape of the plate at a_1 .

Otherwise the remaining features of the apparatus are the same. As illustrated in Figs. 1 to 3, the toothed wheel to be hardened is placed on an axis which rests on two bearings.

5. When the hardening process is being carried out the carriage 2 which supports the burner carriage 3 is clamped to the frame 1 by any suitable known means.

10. The contact of the wheel 5 with the surface of the fixed cam plate 6 as it moves on the latter can be secured by a magnetic device. The wheel 5 may, for example, be kept magnetized by a solenoid 12 situated above it and carried on the arm 4. The wheel will thus be constrained to 15 remain in contact with the cam plate by magnetic attraction.

16. A quick return movement of the burner may be effected by providing a second cam plate and arranging it to be traversed by an idle running 20 wheel which is driven by a weight.

25. Figure 4 illustrates on an enlarged scale a side view of the rear part of the connecting arm 4 shown in Figure 2 on which the magnetized wheel 5 is situated, the solenoid 12 being mounted above the wheel 5 which is driven with constant velocity by means of a motor 13. A bent angle iron 9 carries the cam plate 6. Above the cam plate 6 there is mounted a further cam plate 8 which, in connection with the idle running wheel 7 30 effects the quick return of the burner carriage 3. Figure 5 illustrates on an enlarged scale a plan view of the two cam plates 6 and 8 and the holding device 9. The cam plate 6 is formed in such a manner that, when the burner carriage 3 35 moves to the right, the idle running wheel 7 does not come in contact with the cam plate 8. At the beginning of the return movement, the idle running wheel 7 contacts against the cam plate 8 and removes thereby the magnet roll 5 from the cam plate 6. By the action of the weight 11, the burner carriage 3 now returns into its initial position with an accelerated velocity, the idle running wheel 7 running along the inclined edge of the cam plate 8. As soon as the wheel 7 40 has reached the corner 14, the magnet wheel 5 again comes into contact with the cam plate 8 and the further motion is now again performed by the driving motor 13.

45. As shown in Figures 4 and 5, the cam plates 6 and 8 are fastened by a flat iron or an angle iron to the carriage 2 which is illustrated completely in Figures 1 and 2.

I claim:

5. 1. Apparatus for heating metal articles, particularly toothed wheels by means of the blow pipe flame for the purpose of subsequent hardening, which comprises a burner carriage movable parallel to the surface to be heated, an arm 10 slidably mounted on the carriage and movable towards and from the article, a fixed cam plate, and a driving wheel carried on the arm, means for rotating said driving wheel with a constant velocity, a magnetic device connected with the 15 wheel in such a manner as to constrain the driving wheel to follow the cam contour, and thereby to move the burner parallel to the surface to be heated at a velocity determined by the shape of the cam plate.

20. 2. Apparatus for heating metal articles, particularly toothed wheels by means of the blow pipe flame for the purpose of subsequent hardening, which comprises a burner carriage movable parallel to the surface to be heated, an arm 25 slidably mounted on the carriage and movable towards and from the article, a fixed cam plate, and a driving wheel carried on the arm, means for rotating said driving wheel with a constant velocity, a magnetic device connected with the 30 wheel in such a manner as to constrain the driving wheel to follow the cam contour, and thereby to move the burner parallel to the surface to be heated at a velocity determined by the shape of said cam plate, a second fixed cam 35 plate, an idle running wheel, also carried on said arm and adapted to follow the contour of said second fixed cam plate for a portion of the periphery of the latter corresponding to the return movement of the arm, whereby to move the 40 driving wheel out of fixed relation with said first fixed cam plate, during such return movement, and a driving weight adapted to actuate said idle running wheel whereby to move the latter along said portion of the periphery of said second fixed cam plate providing a quick return motion of 45 said arm.

HERMANN HOLLER.
